SECONDARY VENDING ATTACHMENT FOR
VENDING MACHINESMarshall F. Karst and Grover I. Titus,
Des Moines, Iowa

Application December 18, 1934, Serial No. 758,110

12 Claims. (Cl. 273—138)

This invention relates to a secondary vending attachment for vending machines and is designed primarily for the automatic delivery therefrom, substantially with the delivery of an article of merchandise from the vending machine, an article such as a card or ticket provided with any desirable printed matter thereon, but it is to be understood that an attachment, in accordance with this invention may be employed in any connection which it may be found applicable.

The primary object of the invention is to provide, in a manner as hereinafter referred to, a secondary vending attachment for connection to a coin controlled vending machine and releasable by the controlling mechanism of the latter for the purpose of automatically delivering from the attachment an article such as a card or ticket simultaneous with or subsequent to the delivery of an article of merchandise from the vending machine with which the attachment is employed.

Further objects of the invention are to provide, in a manner as hereinafter set forth, a secondary vending attachment for vending machines, and which is comparatively simple in its construction and arrangement, strong, durable, compact, thoroughly efficient in its use, conveniently released for delivery purposes, readily installed with respect to vending machines with which it is to be used and comparatively inexpensive to set up.

To the above ends essentially and to others which may hereinafter appear, the invention consists of such parts and such combination of parts which fall within the scope of the invention as claimed.

35 In the drawings:

Figure 1 is a vertical sectional view illustrating the housing of a vending machine showing the adaptation with the latter of the vending attachment in accordance with this invention and with certain elements of the attachment in released position.

Figure 2 is a view similar to Figure 1 with the attachment in locked position.

45 Figure 3 is a fragmentary view in vertical section illustrating the position of certain elements of the attachment during the operation of the latter,

Figure 4 is a section on line 4—4, Figure 1,

50 Figure 5 is a sectional plan of the attachment on line 5—5, Figure 1,

Figure 6 is a front elevation of the selector assembly,

55 Figure 7 is a top plan view of the selector assembly,

Figure 8 is a front elevation of the selector bar, and

Figure 9 is a rear elevation of the guide bar. With reference to Figures 1, 2, 3 and 5 the housing or casing of the vending machine, with which the attachment is to be used in connection with, is indicated at 10. The major portion of the front of housing 10 is open, as indicated at 11. The remaining portion of the front of housing 10 is closed by a wall member 12. The housing 10 includes a pair of side walls 13, 14, a top wall 15, a rear wall 16 and a bottom 17.

The vending attachment, in accordance with this invention, is attached to housing 10, constitutes a closure for the open front portion 11 and extends outwardly with respect to the wall member 12. The attachment is arranged between the side wall 13, top wall 15, bottom 17 and member 12 of housing 10.

With reference to Figures 1 and 5: The attachment includes a front section 20 formed of a vertically disposed rectangular part 21, a pair of oppositely outwardly inclined side parts 22, 23, a rearwardly extending upwardly inclined top part 24, a rearwardly inclined bottom part 25, a forwardly extending trough 26 integral with the outer face of the lower portion of the rectangular part, and a rectangular elongated slot 27 transversely of part 21 in proximity to the bottom of the latter. The slot 27 opens into the trough 26 above the bottom of the latter. The purpose of slot 27 will be hereinafter set forth. The side part 22 has a vertical shoulder 28 adjacent its rear edge.

When the section 20 is arranged in position relative to housing 10 the part 24 abuts top wall 15, the part 22 extends against the inner face of wall 13, the shoulder 28 on part 22 abuts the forward edge of wall 13, part 23 extends to oppose the inner edge of member 12 and the part 25 seats on bottom 17. Suitable means, not shown, is employed for locking section 20 with housing 10.

With reference to Figures 1, 2, 3 and 5: There is arranged within the section 20 a vertically disposed open bottom combined guide and storage structure 29 providing a series of vertically disposed parallel storage compartments 30 open at their bottoms. The structure 29 includes a container formed of a rear wall 31, a top wall 32, a pair of side walls 33, a series of spaced vertically disposed parallel partitions 34 corresponding in height to that of the wall 31 and a front wall 35 of less height than that of the wall 31 and is formed at its lower end with a forwardly extending right angular disposed flange 36. The rear wall 31 and side walls 33 are formed from one

length of material. Arranged below the walls 31, 33 and 35 is a horizontally disposed stationary plate 37 extending forwardly to below flange 36, rearwardly from wall 31 and laterally with respect to walls 33. The upper face of plate 37 aligns with the lower wall of slot 21. The side walls 33 have integral with the lower portions of the outer faces thereof angle pieces 38 which rest upon and are anchored to the upper face of plate 37 whereby the bottom edges of said side walls seat directly upon the upper face of plate 37. The rear wall 31 is of less height than the side walls 33. The upper end of rear wall 31 is flush with the upper ends of the walls 33 thereby providing, in connection with plate 37, a groove 39 at the rear of said storage compartments 30 which extend from one side wall 33 to the other side wall 33. The compartments 30 are provided by the coaction of the rear wall 31, side walls 33, partitions 34 and front wall 35. The partitions have their lower edges seated directly upon the upper face of plate 37. There is positioned upon the plate 37, forwardly with respect to wall 35, a bar 40 formed on its inner side with a series of spaced parallel vertical grooves 41 which receive extensions 42 on the partitions 34. The side walls 33 also extend into grooves 41. This arrangement prevents the buckling or bending of the partitions. The lower face of bar 40 is formed with a groove 43 of a width corresponding to the distance between one side wall 33 to the other side wall 33. The groove 43, in connection with the plate 37 and partitions 34, forms outlets for the passage of the articles 44 which are to be selectively dispensed from the compartments 30. The flange 36 on the lower end of front wall 35 seats upon bar 40 and is hinged therewith, as at 45, whereby the wall 35 may be shifted away from the side walls 33 for the purpose of having access to the compartments 30. The top wall 32 is soldered or otherwise secured upon the upper ends of the walls 31, 33 and the partitions 34. The top wall 32 carries a resilient latch 46 for detachably securing the front wall 35 in closure position with respect to the front of the compartments. Positioned upon the plate 37 and arranged against the rear wall 31 is a bar 47 (Figure 5) constituting a combined guide, stop and retainer element for a purpose to be referred to. The bar 47 has enlarged end portions 48 and a reduced intermediate portion 49. Hold-fast means 50 extend through the end portions 48 for anchoring bar 47 to plate 37. The lower face of the bar 47 is formed with a series of parallel grooves 51 (Figure 4) for the passage of ejectors to be referred to. The upper walls of the grooves 51 are flush with the bottom edge of rear wall 31. The grooves constitute guides for the ejectors, to be referred to. The side walls of said grooves 51 prevent the ejectors from shifting laterally with respect to their path of travel in either direction.

Arranged rearwardly of the wall 31 of the structure 29 is a series of oscillatory operating levers 52 (Figure 4) for a series of ejectors 53. The number of levers and ejectors correspond to the number of compartments 30. The levers 52 are of like construction and each consists of an upper and a lower arm 54, 55 respectively (Figures 1, 2 and 3) disposed at an angle with respect to each other. The arm 54 is of materially greater length than the arm 55. The levers are pivoted at the point of joinder of the two arms thereof on a stationary pivot rod 56 mounted in supports 57, 58. The arm 54 depends from the arm 55. The latter extends rearwardly at an

upward inclination from the arm 54 and has connected to its rear end a controlling spring 59 depending from a support 60, secured to the top wall 15 of housing 10. The lower end of the arm 54 is extended between a pair of oppositely disposed spaced parallel angle pieces 61 secured upon the upper face at the rear end of an ejector 53. The lower end of arm 54 (Figure 1) is slotted as at 62. Carried by the pair of angle pieces is a pivot 63 which extends through slot 62. The arm 54, between its transverse median and its upper end has adjustably secured thereto a rearwardly extending pointed combined stop and releaser element 64 for the lever.

Each ejector 53 is in the form of a rectangular slide 65 which travels upon the upper face of the plate 37 through a groove 51 at the bottom of a compartment and extends, when ejecting or vending an article, to the forward face of bar 40. The angle pieces 61 and pivots 63 form parts of the ejectors.

Arranged rearwardly of and spaced from the operating levers 52 (Figures 1, 2, 3 and 4) is a selector assembly for the levers 52. The assembly comprises a selector bar or element 66 formed (Figures 6, 7 and 8) with a set of spaced vertical parallel slots 67, 68, 69 and 70. The bar 66 is of oblong contour standing on its lower lengthwise edge 71. The latter has depending therefrom a pair of outer and an inner depending lug indicated at 72, 72' and 73 respectively. The lugs are arranged in spaced relation. The lug 73 has attached thereto one end of a controlling spring 74 for bar 66. The latter is slidably mounted in the upper ends of a pair of spaced brackets 75, 75' attached to the frame 76 of the vending machine when the attachment is used. Associated with the bar 66 is a shifting lever 78 therefor which is pivoted intermediate its ends, as at 79, to a lug 80 formed on and extending rearwardly from a depending portion 80' of a horizontally disposed yoke 81 secured to the rear of the upper ends of the brackets 75, 75'. The forward end of lever 78 is arranged below the edge 71 of bar 66. The forward end of lever 78 has a curved nose 82 which is adapted to engage the lug 72 and shift the bar 66 for a purpose to be referred to. Attached to the lever 78 is the other end of spring 74. The latter tends to maintain the nose 82 in abutting engagement with lug 72. The lever 78 has its rear end arranged below a slotted link 84 which is pivoted, as at 85, to the rear end of the controlling lever 86 of the attachment. The lever 78 has attached to its rear end a slidable screw 87 which extends through the slot 88 in and slides on the link 84. Fixed at one end to the screw 87 is a controlling spring 89 for normally holding screw 87 clear of the end 90 of the slot 88. The other end of spring 89 is anchored to the pivot 85. The controlling lever 86 includes a vertical intermediate part 91, an upper horizontally disposed rearwardly extending straight part 92 disposed at right angles to the upper end of part 91 and a horizontally disposed rearwardly directed hook-shaped part 93 extending in an opposite direction with respect to part 92 and also at right angles to the intermediate part 91. The part 93 is arranged above the lower end of the part 91. The lower end of bracket 75' is provided with a bearing 93' for the lower end of part 91. The upper end of bracket 75' has a rearwardly extending bearing 94 for the upper portion of part 91. The side wall 13 of housing 10 is formed with a clearance 94' for the bar 66 (Figure 4).

The controlling lever 86 is operated from the controlling mechanism 95 (Figures 6 and 7) of the vending machine with which the attachment is employed. The said controlling mechanism is 5 of the well known type disclosed by Figures 1, 2, 11 and 12 of Patent 1,767,603, indicated on the drawings of said patent by the reference characters 133 to 139 and 141 to 157 and as described in lines 116 to 130, page 3, and in lines 1 to 82, 10 page 4 of said patent. The controlling mechanism, as referred to, includes what may be termed a slidable spring controlled rack and a set of slides and which are indicated on the drawings of this application at 96, 96' respectively. The part 93 15 of the lever 86 permanently bears against the front portion of the rack 96, and is normally held in such position by a spring 97 which is attached to yoke 81 and to the lever 78. On the operation of the vending machine with which the attachment is employed, the rack 96 moves forwardly acting on part 93 of lever 86 for shifting it to transmit motion to the lever 78 whereby the latter will be shifted away from lug 72 against the action of spring 74. Carried by the bracket 75' 20 below the bar 66 is an adjustable set screw 97' for arresting the sliding movement of bar 66 in a direction towards rack 96. The screw 97' is adapted to coact with the lug 72' to obtain a function hereinafter referred to.

30 The attachment includes an operating mechanism which is common to all of the ejectors. The said ejectors operating mechanism includes a normally stationary horizontally disposed spring controlled U-bar 98 (Figures 1, 2, 3 and 5) functioning when active to operate a selected ejector. The normal position of bar 98 is as shown in Figure 1, that is over and free of connection to plate 37, as well as bearing against the lower ends of the arms 54 of the levers 52. The sides of bar 35 98 are indicated 99, 100. The arm 99 (Figure 5) is formed with a wide rear portion 101 provided with upstanding spaced bumper and trip lugs 102, 103 respectively. The bumper lug 102 is offset laterally with respect to the arm 99. The trip 40 lug 103 is pointed and is arranged at the rear end of arm 99. The arms 99, 100 are formed with openings 104 for the purpose of securing the rear end of bar 98 upon a shaft 105 which is journaled in bearings 106, 107. A pair of operating springs 45 107' is provided for the bar 98. These springs are mounted about shaft 105 and each has one end bearing against one of the sides of bar 98 and its other end bearing against the lower face of plate 37. The shaft 105 is arranged slightly above the 50 rear of plate 37.

The attachment includes a combined elevating restoring trip mechanism for the ejectors operating mechanism and which consists of a shiftable lever arm 108 (Figures 1, 2 and 3) which is 55 pivotally mounted on the shaft 105. The bumper 102 (Figure 2) is positioned in the path of movement of the forward side edge of lever arm 108. Pivotally connected to the lever arm 108, in proximity to, but above the arm 99 is a trip member 109 which extends rearwardly with respect to the rear end of arm 99 and is formed on and intermediate the ends of its bottom edge with a shoulder 110. The rear portion of member 109 is reduced and of curved contour. The shoulder 110 60 is for coaction with the trip lug 103 for a purpose to be referred to. Arranged below and spaced rearwardly adjacent with respect to bar 98 is a bracket 111 (Figures 1, 2 and 3) carrying an 65 adjustable member 112 upon which the member 70

109 slides when in the position shown in Figure 3.

The attachment includes an automatically releasable safety mechanism or device to prevent the operation of the operating mechanism for the ejectors until the selector bar of the selector 5 assembly has been adjusted to the desired point for selection of that ejector or ejector device which is to be operated. The attachment also includes a manually releasable locking mechanism for the ejectors operating mechanism. It 10 is necessary to release the safety mechanism or device and the locking mechanism before an ejector device may be operated to discharge the selected article or card.

The automatically releasable safety mechanism 15 or device includes (Figures 1, 2 and 3) a retainer 113 formed with an upstanding nose 114 at its forward end. The rear end of retainer 113 is pivoted, as at 115, to the lower end of an inclined upstanding main operating bar 116 which is 20 mounted intermediate its ends upon a pivot 117 carried by a plate 118 anchored to the inner face of side wall 13 of housing 10. The forward end of retainer 113 is pivotally connected with the upper end of lever 109, as at 115'. Carried by 25 plate 118 is a pivot 119 upon which is mounted a spring controlled locking bar 120 which inclines upwardly from front to rear. The bar 120 has a reduced forward end edge 121 constituting an abutment for a purpose referred to. The rear 30 end edge 122 of bar 120 is beveled. Mounted in close proximity to its upper end upon pivot 117 is a shiftable spring controlled depending releasing lever 123 formed with a lateral flange 124 on its lower portion for the purpose of shifting bar 116 against the action of its controlling spring. The upper end of lever 123 has a forwardly directed enlarged angularly disposed part 125 provided with a vertically disposed threaded opening 126. Mounted in the opening 126 is an 40 adjustable shifter 127 for the locking bar 120. The shifter 127 is arranged over the edge 122 of bar 120 whereby when the lever 123 is shifted forwardly against the action of the controlling spring 128, the shifter 127 will be moved clear 45 of edge 122 to enable the rear portion of bar 120 to be moved upwardly on its pivot due to the action of controlling spring 128 to arrange the bar 120 in locking position. The bar 120, when in its locking position, has its edge 121 abut the 50 nose 114 on retainer 113 as is shown in Figure 2. The rearward movement of lever 123, due to the action of its controlling spring 128 will provide for the shifter 127 engaging edge 122 to move the rear portion of bar 120 downwardly for the 55 purpose of shifting end edge 121 of said bar 120 clear of nose 114 thereby automatically unlocking the safety mechanism or device.

The lever 123 is shifted against the action of its controlling spring 128 by an element of the 60 vending machine with which the attachment is used. As shown, by way of example, the means employed for shifting lever 123 indicated at 129, is in the form of the well known horizontally disposed oscillatory bar employed in coin controlled vending machines of known type, and which is as indicated at 74 on Figures 3, 4, 5 and 6 of Patent 1,854,479. The bar 129, which corresponds to bar 74 of Patent 1,854,479, is operated by the means employed for operating the 65 bar 74 referred to, or in other words the bar 129 corresponds to the oscillatory bar 74 of Patent 1,854,479.

The manually releasable locking mechanism 70 75

includes a locking bar 130 which is eccentrically mounted on pivot 119. The bar 130 inclines upwardly from front to rear, is rabbeted at its forward end to form a nose 131 and a shoulder 132 and is provided at its rear end with a hook 133. That portion of bar 130 extending rearwardly from pivot 119 is of materially less length than that portion extending forwardly from said pivot. A controlling spring for bar 130 is indicated at 134 and which is attached to hook 133. The bar 130 is offset intermediate its ends as at 135. Extending through the offset part of bar 130 is an upstanding link 136 pivoted to bar 130, as at 137. The link 136 extends a substantial distance above bar 130 and is pivotally connected, as at 138, to a lever arm 139 which is fixed upon the inner end of a shaft 140, journaled in and extending through the plate 118 and side wall 13 of housing 10. The outer end of shaft 140 carries a push member 141 for rocking the shaft 140 clockwise against the action of controlling spring 134. Suitable stops 142 (Figure 1) are provided for limiting the movement of member 141 in opposite directions. When the locking mechanism is in non-released position the forward end of bar 130 will overlap the rear upper corner of lever 108, as shown in Figure 2. On shifting shaft 140 from member 141 in a clockwise direction lever arm 139 will be elevated, carrying link 136 therewith, which in turn will elevate the forward portion of bar 130 on its pivot whereby the rabbeted end of bar 130 will be moved clear of the upper end of lever 108 whereby the latter is released for actuation.

The main operating bar 116 is adjustably connected at its upper end, as at 143, to a controlling spring 144. The plate 118 carries an adjustable stop 145 for the bar 116. The plate 118 has an opening 145' which registers with clearance 94'. The articles shown in the compartments 30, by way of example, are cards. The stack of cards in each compartment may have mounted thereon a weight. The thickness of an ejector slide 65 is slightly less than that of a card.

The operation of the attachment is as follows: When the vending machine with which the attachment is employed is operated on the insertion of a coin it provides, first, the actuation of the mechanism 95 thereof and on the actuation of the said mechanism the rack 96 moves forwardly carrying the part 93 of lever 86 therewith whereby lever 86 will cause nose 82 to move away from lug 72 and apply tension to spring 74, and at this point bar 129 of the vending machine moves in a direction to engage and move lever 123 to an extent to have flange 124 engage the rear edge at the lower portion of bar 116 for moving the said portion forwardly to the dotted line position shown in Figure 2 whereby the elements 108, 109 and 113 will assume the full line position (Figure 2) to provide for the element 108 bearing on the bumper lug 102 and forcing U-bar 98 down against plate 31 thereby forcing the arms 54 of levers 52 forwardly to move the elements 64 clear of bar 66 and allow the latter to shift to position lug 72 against nose 82. At this point the locking bars 120, 130 are in engaged position, as shown in full lines, Figure 2. At this point the operating handle of the vending machine, with which the attachment is employed, releases the mechanisms of said machine. At this point, bar 129 moves back slowly and when bar 129 moves to about three fourths of its return movement, just about at the point before the shifter 127 engages the edge 122 of bar 120, the rack 96 of the

vending machine, which has its movement controlled, drops back rearwardly the distance of one, two or more teeth, which in turn, enables the part 93 of lever 86 to move back, whereby the spring 97 will maintain the part 93 in engagement with rack 96, which in turn, will enable for the coaction of lever 78 and lug 72 to shift bar 66 in a direction towards rack 96. The distance of the shift of bar 66 is determined by the extent of the rearward shift of rack 96. On the shift of bar 66 in either direction one of the openings or slots therein is arranged to allow an element 64 to move therethrough. Such element 64 is carried by that ejector device which is to be operated. After the bar 66 has been shifted to the desired position it remains there until the attachment is operated again. When the bar 66 has been shifted to the desired position, the bar 129 has arrived at the extent of its rearward travel which allows lever 123 to assume the full line position in Figure 3, whereby said lever 123 will act upon the safety mechanism to release it and at this point the manually operated locking mechanism may be released by operating the member 141 in a direction to provide for the clockwise rocking of shaft 140. After the safety mechanism and the manually operated locking mechanism have been released the lower portion of main bar 116 is moved rearwardly by its controlling spring and shifts elements 108, 109 and 113 to the full line position shown in Figure 3, whereby the trip lug 103 will engage shoulder 110 and cause the raising of the U-bar 98 to the position shown in Figure 3. At this point the selected ejecting device which is to be operated will assume the position shown in Figure 3, that is forwardly of U-bar 98 and in alignment with the article which is to be ejected thereby. Upon the completion of the rearward travel of the lower portion of the main bar 116, the trip lug 103 has been moved clear of shoulder 110 whereby the U-bar 98 is released from its position shown in Figure 3 and acts to operate the selected ejector device. The operation of the U-bar 98 is caused by the springs 108 and these latter provide for the U-bar 98 assuming the full line position shown in Figure 1 and which acts to hold the levers 52 in their normal position before selection.

The manually operated locking mechanism may be released at any time, that is before or after the release of the safety mechanism, but the operation of the attachment cannot be had until after the safety mechanism has been released on the complete operation of the vending machine.

What we claim is:

1. In a secondary vending attachment for vending machines, a set of selectable article ejector devices, a spring controlled selector assembly including a horizontally shiftable selector bar common to said devices and adapted to have its operation governed by the controlling mechanism of the machine with which the attachment is employed, a storage structure for the articles to be vended including a guide for each ejector device, and a releasable normally inactive latched spring controlled operating structure for and common to the selected ejector devices and adapted to have its operation governed from a moving part of the machine with which the attachment is employed.

2. In a secondary vending attachment for vending machines, a set of selectable article ejector devices, a spring controlled selector assembly including a horizontally shiftable selector bar com-

mon to said devices and adapted to have its operation governed by the controlling mechanism of the machine with which the attachment is employed, a storage structure for the articles to be vended including a guide for each ejector device, a spring controlled operating mechanism for and common to the selected ejector devices and for holding said devices in non-selected position, a spring controlled elevating, trip and restoring mechanism for and governing the operation of said operating mechanism, a spring controlled normally active automatically releasable safety mechanism for normally maintaining the combined elevating, trip and restoring mechanism in restoring position, a manually releasable spring controlled locking mechanism for normally maintaining the combined elevating, trip and restoring mechanism in restoring position and operated independently of said safety mechanism, and means operated from a moving part of the machine with which the attachment is employed for governing the elevating and tripping action of the combined elevating, trip and restoring mechanism and for governing the operation of said safety mechanism.

3. In a secondary vending attachment for vending machines, a set of selectable article ejector devices, a spring controlled selector assembly including a horizontally shiftable selector bar common to said devices and adapted to have its operation governed by the controlling mechanism of the machine with which the attachment is employed, a storage structure for the articles to be vended including a guide for each ejector device, a releasable normally inactive latched spring controlled operating structure for and common to the selected ejector devices and adapted to have its operation governed from a moving part of the machine with which the attachment is employed, and a manually releasable spring controlled locking mechanism for said operating structure.

4. In a secondary vending attachment for vending machines, a set of selectable article ejector devices, a spring controlled selector assembly including a horizontally shiftable selector bar common to said devices and adapted to have its operation governed by the controlling mechanism of the machine with which the attachment is employed, a storage structure for the articles to be vended including a guide for each ejector device, a normally inactive spring controlled operating structure for and common to the selected ejector devices having its operation governed from a moving part of the machine with which the attachment is employed, a normally latched spring controlled safety device for said operating structure shifted to active position by a part of said operating structure, and a manually releasable spring controlled locking structure for said operating structure operated to released position independently of said safety device.

5. In a secondary vending attachment for vending machines, selectable article ejector devices, operating means for and common to the selected ejector devices, said operating means adapted to have its operation governed by a movable part of the machine with which the attachment is employed, a normally active safety device for said operating means having its operation controlled by a moving part of said operating means, and a releasable locking mechanism for said operating means independent and operated independently of said safety device.

75 6. In a secondary vending attachment for

vending machines, a spring controlled article ejector operating means, a spring controlled normally latched setting and releasing mechanism for said operating means, said means and mechanism having coacting parts for tripping said means to release it from its set position to enable the operation thereof and for holding down said means after it has operated the ejector to prevent movement of the latter.

7. In a secondary vending attachment for vending machines, a spring controlled article ejector operating means, a spring controlled normally latched setting and releasing mechanism for said operating means, said means and mechanism having coacting parts for tripping said means to release it from its set position to enable the operation thereof and for holding down said means after it has operated the ejector to prevent movement of the latter, a spring controlled element operated from a moving part of the machine with which the attachment is employed for restoring said mechanism to holding position relative to said means, a spring controlled releasable safety device having its movement governed by said element and releasably engaging with said mechanism for normally latching it in holding position, a releasable locking means engageable with said mechanism for maintaining it in holding position, and said locking means being independent of and independently operable with respect to said safety device.

8. In a secondary vending attachment for vending machines, a series of upstanding article containing compartments discharging at their bottoms, selectable ejector devices for selective coaction with the bottoms of said compartments for vending the articles, means at the bottom of said compartments to provide guides for said devices, a spring controlled ejector selector assembly arranged rearwardly of the ejectors and having its operation controlled by the controlling mechanism of the vending machine and including a horizontally shiftable apertured selector bar, and a spring controlled operating structure common to the selected ejector devices and having its operation governed by a moving part of the vending machine and a spring controlled normally active releasable safety device for latching said structure in inactive position and having its active and inactive positions governed from a part of said mechanism.

9. In a secondary vending attachment for vending machines, a series of upstanding article containing compartments discharging at their bottoms, selectable ejector devices for selective coaction with the bottoms of said compartments for vending the articles, means at the bottom of said compartments to provide guides for said devices, a spring controlled ejector selector assembly arranged rearwardly of the ejectors and having its operation controlled by the controlling mechanism of the vending machine and including a horizontally shiftable apertured selector bar, a spring controlled operating structure common to the selected ejector devices and having its operation governed by a moving part of the vending machine and a spring controlled normally active releasable safety device for latching said structure in inactive position and having its active and inactive positions governed from a part of said mechanism, and a spring controlled releasable locking mechanism for normally locking said structure in inactive posi- 75

tion independent of and releasable independently of the said safety device.

10. In a secondary vending attachment for vending machines, a selected article discharging structure adapted to having its movement governed by the controlling mechanism of and a moving part of the vending machine, said structure including a spring controlled selector assembly and an article discharging mechanism, 10 a normally active safety device for normally maintaining said mechanism inactive and having its active position controlled from a part of said mechanism, and a releasable locking means for normally maintaining said mechanism 15 inactive and independent of the said safety device.

11. In a secondary vending attachment for vending machines, a selected article discharging structure adapted to having its movement 20 governed by the controlling mechanism of and a moving part of the vending machine, said structure including a spring controlled selector assembly and an article discharging mechanism, a normally active safety device for normally 25 maintaining said mechanism inactive and having its active position controlled from a part of

said mechanism, and a releasable locking means for normally maintaining said mechanism inactive and independent of the said safety device, said structure having parts coacting with said safety device and locking means for normally maintaining said mechanism inactive, the said parts coacting with said safety device and locking means being spaced from each other. 5

12. In a secondary vending attachment for vending machines, a selected article discharging 10 structure adapted to have its movement governed by the controlling mechanism of and a moving part of the vending machine, said structure including a spring controlled selector assembly and an article discharging mechanism, 15 a normally active safety device for normally maintaining said mechanism inactive and having its active position controlled from a part of said mechanism, said mechanism and safety device being spring controlled, and one of the 20 parts of said structure and one end of said device capable of being engaged in overlapping relation to maintain said mechanism in inactive position. 25
